COMBINED BRACELET, MEMORANDUM PAD HOLDER, AND PENCIL

Avonelle Streed, Hollywood, Calif.

Application June 6, 1957, Serial No. 46,506

Term of patent 3½ years

(Cl. D45—4)

Fig. 1 is a top perspective view of a combined bracelet, memorandum pad holder, and pencil showing my new design;

Fig. 2 is a top perspective view with the container lid in open position;

Fig. 3 is a bottom perspective view;

Fig. 4 is a side elevational view looking from the right of Fig. 2;

Fig. 5 is an enlarged, fragmentary sectional view taken on the line 5—5 of Fig. 1; and

Fig. 6 is an enlarged, fragmentary sectional view taken on the line 6—6 of Fig. 1.

I claim:

The ornamental design for a combined bracelet, memorandum pad holder, and pencil, substantially as shown.
